Primary Examiner — Catherine R Oliver-Garcia(74) Attorney, Agent, or Firm — Bacon & Thomas, PLLC(57) CLAIM

The ornamental design for a belt, as shown and described.

DESCRIPTION

FIG. 1 is a perspective view of a belt showing my new design;

FIG. 2 is a front view thereof;

FIG. 3 is a top view thereof;

FIG. 4 is a right view thereof;

FIG. 5 is a left view thereof;

FIG. 6 is a rear view thereof; and,

FIG. 7 is a perspective view thereof, which has been folded and secured by straps.

The broken lines depict environment and are included for the purpose of illustrating only and form no part of the claimed design.
